MANUFACTURE OF SYNTHETIC FIBERS

Jan J. Schilthuis and Johan D. W. Hubbeling,
Enka, N. C., assignors to American Enka Corporation, Enka, N. C., a corporation of Delaware

Application July 27, 1938, Serial No. 221,615

3 Claims. (Cl. 18—8)

This invention relates to a process of and apparatus for producing wound thread packages, and more particularly the invention is directed to the production of packages formed from rayon or any other type of synthetic fiber by the bobbin spinning process in which the freshly formed thread is wound upon collecting bobbins in such a condition that it is permeable to the treating liquids to which such thread is subjected during the after treating procedures.

It is generally recognized that advantages result from the gradual shortening of the length of stroke of the traverse guide during the winding of a thread package which is to be subjected to after treatment, since such shortening of the stroke will cause slanting or conical ends to be formed on the package by the thread layers. This practice of producing conical ends during the formation of the layers of thread has the advantage of avoiding "over-winding" with resultant entanglement of the thread at the ends of the layers.

A number of mechanisms have been constructed for the purpose of controlling the stroke of the traverse guide in such a way that conical ends will be formed on the thread package being wound, but the use of such mechanisms in the conventional way has not been found to be entirely satisfactory for the reason that packages so formed are not readily permeable to the after treating liquids. This objectionable characteristic is encountered particularly in the outer portions of the wound packages. It has been found that in the conventional use of a traverse guide driven by a stroke shortening mechanism, the angle between the thread being wound into the package and the axis of the bobbin increases during the building up of the package to such an extent that the crosswind of the outer portions of the resultant package is not sufficiently open for proper after treatment.

It is an object of the present invention to provide a mechanism for operating a traversing thread guide in such relation with respect to the collecting bobbin that tapered or conical ends are formed on the package as it is produced while the angles between corresponding superimposed thread convolutions and the axis of the bobbin are maintained substantially constant to cause the corresponding superimposed convolutions to be substantially parallel. The invention further contemplates a process of producing a thread package having the thread incorporated therein

as specified, to thereby provide a thread package in which the crosswind is relatively open.

Additionally, the invention has as an object the provision of mechanism for winding thread such as rayon on foraminated or collapsible bobbins in such a manner that, upon properly positioning the package, the after treating fluid utilized in treating the rayon may be passed uniformly therethrough to thereby effect uniform treatment of the thread forming the respective convolutions with a resultant saving in the time and in the material consumed in the after treating operation.

Other objects and advantages will be apparent from the following detailed description when considered in connection with the accompanying drawing wherein:

Figure 1 is a diagrammatic elevational illustration of one form of mechanism constructed in accordance with the present invention; and

Figure 2 is a side elevation of the mechanism diagrammatically shown in Figure 1.

The present procedure is advantageous in the winding of thread into package form in any instances wherein an open crosswind is desired in the package when wound with a variable stroke traverse guide. While this procedure is particularly beneficial due to the necessity for "after treatment" of synthetic fibers formed from spinning solutions by the well known processes, only a detailed discussion of the present winding mechanism is necessary for a full understanding of the invention.

In referring to the drawing in detail, a spinneret is illustrated at 10 for the formation of filaments 11 by the extrusion therethrough of a spinning solution, such as a cellulosic solution, supplied from a suitable source (not shown). Filaments or thread 11 are conducted to a collecting spool or bobbin 12 and a traversing guide 13 is utilized to direct the thread longitudinally along the spool as the thread is collected thereon due to the rotation of the spool. Spool 12 is preferably driven at a gradually decreasing rotary speed in order that the peripheral or winding speed of the package will be constant. The spool may be driven by any of the well known mechanisms.

A main drive shaft 14 is utilized to drive the traverse thread guide 13 in a manner independent of the control in the change in the length of its stroke and also its frequency of traverse. In the form of mechanism illustrated a change speed mechanism 15 known as the Reeves drive

is utilized, the change speed mechanism being provided with a sprocket 16 over which is passed a chain 17 which at its opposite end rides upon a sprocket 18 keyed to shaft 14. While the invention has been illustrated in connection with a change speed mechanism of the Reeves drive type, it is to be understood that any suitable change speed mechanism may be used in substitution therefor.

Shaft 14 is operated at a constant predetermined R. P. M. and a shaft 19 of the change speed mechanism to which sprocket 16 is keyed is accordingly operated at a constant R. P. M. A pair of cones are keyed to but mounted for longitudinal movement upon shaft 19 and a belt 21 is mounted so that its edges are in engagement with the cones. A pair of cones 22 similar to cones 20 are keyed to and mounted for longitudinal movement upon a shaft 23 which latter mentioned cones are engaged by the belt 21 in the same manner that the belt engages cones 20.

Levers 24 and 25 are positioned on opposite sides of the belt 21 and cones 20 and 22 and these levers are pivoted midway between shafts 19 and 23. Each of the levers 24 and 25 is secured to the hub of an adjacent cone of each set, in a manner to cause the cones to be moved longitudinally of their respective shafts as the levers are pivoted. It will be seen that if the levers are pivoted so that the cones 20 are caused to approach each other, then the cones 22 will be caused to recede from each other to an equivalent extent. Such action will cause the belt 21 to remain taut but will result in a change in the relative speeds of shafts 19 and 23.

Levers 24 and 25 extend upwardly beyond cones 22 and their upper ends are provided with oppositely threaded means in which are contained appropriate threaded portions of a shaft 26. Shaft 26 is caused to be rotated at a constant speed, since the power therefor is derived from constant speed shaft 19. More explicitly, a sprocket 27 keyed to shaft 19 is utilized to operate a speed reducer 28 through the medium of a chain 29 which rides upon sprocket 27 and a sprocket 30 of the speed reducer. Driven shaft 31 of the speed reducer carries a spur gear 32 which gear meshes with gear 33 on shaft 26 and therefore the operation of shaft 19 causes a very much reduced but constant speed of shaft 26.

Any of the well known stroke modifying mechanisms for controlling the length of the traverse stroke of thread guide 13 may be utilized in the practicing of this invention. One such mechanism which is suitable is described in United States Patent No. 1,869,055 issued to Antonie Jacobus Engel. Therefore, a suitable traverse guide operating, and stroke shortening mechanism is represented at 34. Mechanism 34 is mounted upon shaft 35 and shaft 35 is caused to be rotated by means of variably rotating shaft 23 through the medium of a sprocket 36 keyed to shaft 23, a sprocket 37 and a chain 38 mounted to ride upon said sprockets.

Thread guide 13 is formed with an arm 39 which is secured to shaft 40, and another arm 41 is secured to shaft 40 in such relation that its end engages with a cam 42 of the mechanism designated generally at 34.

In the utilization of this invention, at the initiation of a complete spinning period the usual spinning pumps are set in motion and the filaments are extruded through the spinneret 10. The thread or filaments 11, after being coagulated, is contacted with the thread guide 13 and

the end of the thread is wrapped over the spool 12. Since at the beginning of the usual winding operation the spool is free of thread, the mechanism 34 is set so that the stroke of the traverse guide will extend to the outer dimensions of the package being formed. At this stage in the winding period the cones 20 of the change speed mechanism are positioned wide apart, while the cones 22 are positioned correspondingly close, this positioning of the respective cones being controlled by the movement of shaft 26 and attached levers 24 and 25. The cones are set to effect a predetermined initial speed of shaft 35 upon the rotation of driving shaft 14.

The complete winding period usually consumes several hours and the position of the cam 42 of the mechanism 34 is gradually modified during this winding period so that the crown of the cam is gradually moved toward the center of rotation while the valley of the cam is accordingly moved in a direction away from the center of rotation. While the crown of the cam is always maintained a much greater distance from the center of rotation than is the valley thereof, this modification in the position of the cam causes the traverse guide to move in a path which is gradually reduced at both ends. Therefore, while the thread guide is initially moved in a wide path the gradual reduction in the width of the path causes the thread to be so wound that the package being produced is formed with conical ends.

During the above described operation of the stroke shortening mechanism for the traverse guide, the shaft 26 is slowly rotated through the medium of shaft 19, sprocket 27, chain 29, sprocket 30, the reduction gearing 28, shaft 31 and gears 32 and 33. The movement of shaft 26 gradually causes cones 20 to approach each other while cones 22 are retracted and therefore, the relationship of belt 21 with respect to the cones as a result of the constant drive speed of shaft 14 causes shaft 23 to rotate at a gradually increasing speed and shaft 35 to proportionately increase in speed of rotation due to the connection of gears 36 and 37 by chain 38.

The gradual increase in the speed of shaft 35 is predetermined and as cam 42 is keyed to rotate at the same speed as shaft 35, the frequency or periodicity of traverse of the thread guide by the cam is accordingly increased. The rate of increase in frequency of traverse movement of the guide is substantially inversely proportional to the decrease in the length of the traverse stroke.

Since, in accordance with the present invention, the frequency of the traverse guide is increased during the winding operation, the number of strokes per unit of length of the thread increases proportionately. This would normally cause an objectionable build-up in the center of the package due to the larger number of convolutions formed. Accordingly, an adjustment of the stroke shortening cam is necessary. This may be accomplished usually by decreasing the speed at which the crown of the cam moves toward its center of rotation.

While the mechanism illustrated has been shown in connection with the winding of thread upon a single spool, it is to be understood that the mechanism illustrated in plant practice will be utilized in connection with the simultaneous winding of a plurality of spools.

What we claim is:

1. In a thread winding machine, a thread collector which is driven at a decreasing rotary speed to impart a constant peripheral speed to a pack-

age as it is formed thereon, a thread guide mounted to traverse the collector, means for traversing the thread guide across the face of the collector, means for decreasing the stroke of the thread guide during the winding-on operation, and means for synchronously increasing the frequency of traverse as the traverse stroke is decreased while maintaining the speed of traverse substantially constant.

2. A method of winding rayon thread on a collector in the form of a package having conical ends comprising withdrawing and collecting a thread at a uniform rate of speed from a source of supply, axially guiding succeeding lengths of thread onto the said collector to form successive layers of gradually decreasing length and maintaining constant throughout the winding operation, the angle made by the axis of the said collector with respect to the thread as it is delivered

thereto by increasing the frequency of the traverse stroke while maintaining the speed of traverse constant as the length of the successive layers decreases.

- 5 3. In a thread winding machine, a thread collector, means for winding thread upon said collector at a uniform rate of speed, a thread guide mounted to traverse the collector, means for traversing the thread guide across the face of the collector, means for decreasing the traverse stroke of the thread guide during the winding-on operation and means for gradually increasing the frequency of the traverse guide while maintaining the speed of traverse constant whereby the angle made by the axis of the said collector with respect to the thread as it is delivered thereto is the same throughout the winding-on operation.
